COMBINED AQUARIUM AND LAMP BASE

Bob J. Hullender, P.O. Box 11068,
Santa Rosa, Calif. 95406

Filed July 10, 1972, Ser. No. 270,179

Term of patent 14 years

Int. Cl. D26—05

U.S. Cl. D48—20 D

FIG. 1.

FIG. 2.

FIG. 3.

FIG. 4.

FIG. 1 is a perspective view of a combined aquarium and lamp base showing my new design;

FIG. 2 is a top plan view thereof;

FIG. 3 is a side elevational view thereof; and

FIG. 4 is a sectional view taken along line 4—4 of FIG. 3.

I claim:

The ornamental design for a combined aquarium and lamp base, substantially as shown.
